US00D860205S

(12) **United States Design Patent** (10) **Patent No.:** **US D860,205 S**
(45) **Date of Patent:** **** Sep. 17, 2019**

(54) **STYLUS**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/656,741**

(22) Filed: **Jul. 16, 2018**

(57) **CLAIM**

The ornamental design for a stylus, as shown and described.

DESCRIPTION

FIG. 1 is a perspective view of a stylus showing our new design;

FIG. 2 is another perspective view thereof;

FIG. 3 is a top view thereof;

FIG. 4 is another top view thereof, showing the design rotated 90° from FIG. 3;

FIG. 5 is a rear view thereof; and,

FIG. 6 is a front view thereof.

The dashed broken lines represent structure or features which form no part of the claimed design.

The dot-dash broken lines represent boundaries of the claimed design; the dot-dash broken lines themselves form no part of the claimed design.

1 Claim, 2 Drawing Sheets

Related U.S. Application Data

continuation of application No. 29/577,947, filed on Sep. 16, 2016, now Pat. No. Des. 796,511, which is a continuation of application No. 29/538,660, filed on Sep. 4, 2015, now Pat. No. Des. 771,049.
